UNITED STATES PATENT OFFICE.

EDWARD J. SCHREMP, OF ROCHESTER, NEW YORK, ASSIGNEE, BY MESNE ASSIGNMENTS, TO LIBERTY NATIONAL BANK, TRUSTEE, OF SYRACUSE, NEW YORK.

GARMENT-PRESSING APPARATUS.

Application filed April 19, 1924. Serial No. 707,783.

To all whom it may concern:

Be it known that I, EDWARD J. SCHREMP, a citizen of the United States, and a resident of Rochester, in the county of Monroe and State of New York, have invented a certain new and useful Garment-Pressing Apparatus, of which the following is a specification.

This invention relates to a pressing apparatus particularly applicable for pressing knit goods, as sweaters, underwear, hosiery, and other articles, and intended primarily, but not exclusively for garment factories and laundries, and it has for its object a particularly simple and efficient means for facilitating the arrangement of the articles on the conveyor belt, and means for controlling the operation of the conveyor belt and of the pressing machine.

20 The invention consists in the novel features and in the combinations and constructions hereinafter set forth and claimed.

In describing this invention reference is had to the accompanying drawings in which like characters designate corresponding parts in all the views.

Figure 1 is a fragmentary front perspective view of the left hand portion of the machine embodying my invention.

30 Figure 2 is a fragmentary front perspective view of the right hand portion of the machine.

Figure 3 is a fragmentary side elevation of the mechanism of the pressing machine 35 for actuating the press head of such machine.

Figure 4 is a detail view of the actuating mechanism for clamping and facilitating arrangement of the garments and other articles on the receiving end of the conveyor belt.

Figure 5 is an enlarged fragmentary sectional view of the remote control switch for controlling the operation of the automatic breaker switch and the extent of movement of the belt during each operation.

Figure 6 is a diagrammatic view of the electrical circuits controlling the motor.

50 This apparatus comprises generally a pressing machine, including cooperating pressing elements, one of which is movable toward and from the other, a conveyor belt running over the lower pressing element, that is, between the pressing elements, means

for controlling the actuation of the movable 55 pressing element and the belt, and means for clamping the articles on the receiving end of the belt for facilitating the stretching or the arrangement thereof while the belt is idle.

This machine is of the type shown in the patent to Schaufler, No. 1,511,582, granted on Oct. 14, 1924, for work conveyor for laundry and garment pressing machines.

This pressing machine may be of any suitable form, size and construction, and, as here shown, includes a horizontal lower buck 1, a press head 2, movable toward and from the lower buck, it being carried on a suitable frame, and means for actuating the head. The press head is usually carried by a yoke 4 pivoted at 5 between its ends to a standard 6, rising from the frame. The front arm of the yoke carries the press head 2 in any well known manner, and the rear arm is connected to suitable actuating mechanism.

This actuating mechanism includes a lever 7 pivoted at 8, to the frame near the base thereof, toggle links 9, 10, pivoted together at 11, the link 9 being pivoted to the frame usually on the same pivot 8 that connects the lever 7 to the frame; and the link 10 being pivoted at 12 to the rear arm of the yoke 4. The link 10 usually consists of endwisely adjustable sections, one of 85 which includes a screw 13, actuated by a hand wheel 14 to lengthen or shorten the link 10, as will be understood by those skilled in the art, for the purpose of adjusting the machine to the thickness of the 90 work.

The lever 7 is provided with a face 15 with which coacts an intermittently operated cam 17, actuated by a suitable motor and controlled in its actuation by a suitable 95 periodic or half revolution clutch mechanism controlled by a lever 18. The mechanism controlled by the lever 18 operates to permit the cam to be actuated by the motor 19, a one-half revolution upon each operation of the lever 18, one-half revolution depressing the lever 7 and the other half permitting the lever to rise under the influence of a counter weight 20, and a spring 20^a if necessary acting in conjunction with the 105 counter weight.

When the head is up the actuation of the cam 17 depresses the lever 7, but such de-

pression is ineffective upon the yoke 4, unless the press head has first been closed either by hand or by mechanism to nearly straighten the toggle links 10, 11. The head 5 is initially closed by manual operating mechanism, here shown, as consisting of a rock shaft 20^b, journaled in the frame and extending forwardly and rearwardly and having a handle 21 at its front end, a bevel gear 22 at its rear end meshing with the bevel gear 23 carried by the frame, and toggle links 24, 25, mounted on the shaft 26, on which the gear 23 is mounted and on the shaft 12 to which the rear link 10 of the 15 main toggle is connected. Obviously, by turning the handle 21 the toggle links 24, 25, will be straightened from their position shown in Fig. 3, and thus bring down the head toward the lower buck 1, and in so doing nearly straighten the toggle links 9, 10. Thereafter the lever 18 is thrown to connect the cam 17 to the motor, so that, the cam makes a one-half revolution. The motion 20 of the lever 7 is transferred to the toggle links 9, 10, after the links 9, 10, have been straightened by the manual closing of the press head by the operation of the handle 21, by a link 26^a pivoted at 27 to the rear end of the power lever 7, and connected to one or the other of the links 9, 10 by a lost motion connection as a pin and slot connection 29, 30. This link 26^a normally extends rearwardly nearly horizontal and the operation 25 of the lever 7 when the link is in this position is of no effect, but when the head 2 has been closed down toward the lower buck 1, so that, the toggle has nearly straightened, the link is carried upwardly to nearly an upright position, so that, the pin 29 moves to 30 the lower end of the slot, and when the power is applied to the lever 7, the pin 29 then shoulders against the lower end of the slot 30, and hence, thrusts the toggle links 9, 10, into or nearly into their dead center line. 35

The operating mechanism for the press head 2 may be of any suitable form, size and construction, and its construction per se forms no part of this invention.

31 is a conveyor belt, running over the face of the buck 1, and extending beyond opposite ends of the buck 1, suitable distances to permit one operator to place the garments or articles on the end of the belt 40 on one side of the buck 1, while another operator removes the pressed articles from the portion beyond the other end of the buck 1. Preferably both runs or belts run over the face of the buck 1. The belt at its ends runs over suitable rollers as 32, supported respectively by frames 33, 34, on opposite sides of the pressing machine, suitable tables 35, 36, being located between the upper and the lower runs of the belt at opposite sides of the 45 pressing machine.

The lower run of the belt is supported on

rollers 37, 38, 39, and are guided thereby under the tables 35, 36, and over the buck 1. One of the rollers 32 has its axle 40 supported in boxes as 41, slideable in guides 42 carried in opposite sides of the frame 33, and these 50 boxes are adjustable to tighten the belt by means of screws 43 threading through the lugs 44 on the brackets 42 and connected at their inner ends to the boxes 41, and having a suitable handle or wheel 45 at their outer ends.

The means for clamping the garments temporarily on the left hand or receiving portion of the belt preliminary to being moved between the pressing elements, comprises a clamping member or jaw 46 movable toward and from the left hand end portion of the belt 31, means for holding the clamping member in its clamped position, and means for tripping the holding means. As here shown the clamp is carried by lever arms or yoke 47 pivoted on a rod 48 carried by brackets 49 supported on the table 33. A spring 50 tends to move the lever arms 47 to cause said arms to lift the clamping member 46 off the belt. The means for moving the clamping member to its operative position comprises a pedal or lever 51, pivoted between its ends at 52, a link 53 connecting the front arm of the lever 51 to the rear arms of the lever 47. The lever 51 has a treadle or foot plate 54 at its front end. By depressing the lever 51, obviously the clamping member 46 will be brought down onto the work 55 as a sweater or other articles on the receiving end of the belt, so that, the operator by pulling on the sweater can stretch the same into the proper pressing shape or position. The lever 51 is held in its operated position 60 by suitable means as a latch 55 pivoted at 56 to the lever 51, and movable into engagement with a shoulder or detent 57, fixed to the floor or the base of the machine, the latch being acted upon by a suitable spring 58 which causes it to ratchet into engagement with the detent 57.

The latch is released to permit the spring 50 to move the clamping member upwardly 65 out of engagement with the work by a kick-off lever 59, pivoted at 60 to the lever 51, and having an arm 61 arranged to push against the latch 55. The latch 55 may also be tripped by hand by means of a trip lever 62, having a nose 63 arranged in a notch 64 of the latch 55, when the latch is engaged with the hook 57, the lever 62 being pivoted at 65 at its inner end. The lever 62 is operated by a handle 67 suitably pivoted to the table 33 and connected by a link 68 to one arm of an angular or bell crank lever 70 pivoted at 71 and connected by a link 72 to a bell crank lever 73 pivoted at 74 to the frame, the other arm of the bell crank lever 73 being connected by a link 75 to the release lever 62. 75 A suitable spring 76' acting on the bell

crank lever 70 serves to hold the trip lever 62 in its out position.

In operation the operator places the sweater or other garment on the upper run 5 of the belt 30, that is, the portion of the upper run overlying the table 35, then depresses the lever 51 to bring the clamping member 46 down on to the edge of the garment, the latch 55 engaging the detent 57 10 and holding the clamping member 46 in its operated position. The operator then stretches the sweater or other garment to its desired position for pressing, and then releases the clamping member 46 either by 15 operating the trip lever 59 with the foot or operating the trip lever 62 by the hand lever 67.

The means for controlling the actuation of the press head as before stated, comprises a 20 lever 18 which actuates a suitable clutch for connecting the cam 17 to a constantly running shaft. The lever 18 is actuated by means of a handle 76 pivoted to the frame 33 and connected by a link 77 to an arm 78 25 mounted on a rock shaft 79. The rock shaft 59 is suitably connected to the shifting lever 18, to swing it on its pivot 18a. If this lever 76 is operated before the head has been brought down by hand, that is, by means of 30 the handle 21, the cam will merely idle the lever 7, but if the lever 76 is operated after the head has been brought down toward the buck 2, it will actuate the lever 18 to throw in the clutch.

35 The intermittent operation of this lever clutch mechanism forms no part of this invention, and in so far as this invention is concerned, it is merely necessary to bear in mind that the lever 18 controlling the cam 40 will cause the cam to make a half revolution each time that the lever 18 is operated.

The means for controlling the actuation of the belt 31, comprises a start and stop motor M, the shaft S of which is provided 45 with a pulley over which a sprocket chain 80 also runs, and over a suitable sprocket wheel 81 mounted on the axle of the roller 32 at the right hand end of belt.

50 The motor M is controlled by a push button switch 82 operating a switch within the case 83, which switch is connected by conductors within the cable 84 to an automatic breaker switch 85 of any suitable construction. Upon the pressing of the button 82 55 the motor will be energized and move the belt until the belt is stopped. The belt is stopped by a suitable switch 86 located within the case 87 and coacting with shoulders 88 or their equivalent spaced apart at proper 60 intervals along the margin of the belt 31, this switch being moved into and out of engagement with contact 89, in circuit with the magnet of the breaker switch 85. As the breaker switch 85 is a standard article in 65 manufacture, and the construction and oper-

ation thereof is well known, description thereof is thought to be unnecessary.

The operator of the machine while the pressing operation is being performed places new work on the left hand or receiving side 70 of the belt, Fig. 1, moves the clamping member 46 into engagement therewith, by depressing the lever 51, and after the garment has been properly stretched in position releases the clamping member 46 either by depressing the trip pedal 59 or operating the handle 67. He then opens the press head by actuating the handle 76. He then presses the button 82 which energizes the motor M causing the belt to travel a predetermined distance as one-sixth of its length. In operation when the button 82 is pressed the belt travels until one of the shoulders 88 on the belt engages the switch 86 and moves it out of engagement with the contact 87, whereby 80 upon the circuit through the magnet of the breaker switch is broken, and the switch thrown to off position, so that, when the belt travels or overruns out of engagement with the switch arm 86 the circuit is broken at 85 the breaker switch and the belt comes to a stop, while the switch 86 again moves in engagement with the contact 89 for closing the circuit through the magnet control of the breaker switch, so that, the breaker switch is closed and the current will pass through the motor when the button 82 is depressed, thus upon again pressing the button 82 the circuit will be completed through the motor 90 M until the belt travels a sufficient distance to operate the switch 86 to again open or to break the circuit to the magnet control of the breaker at the contact 89. The shoulders 88 are spaced a suitable distance apart to cause the belt to travel a sufficient distance during each operation, to carry the portion of the belt on the lower buck off the lower buck to the right and the portion of the belt containing the work to be pressed between the pressing elements 1, 2. After the belt 100 has traveled approximately one-sixth its length one of the knock-off shoulders 88 engages the switch lever 86 and breaks the circuit through the magnet of the breaker 105 switch 85, so that, the circuit through the feed wires to the motor is broken off, and the motor stops. The operator then turns the handle 21 to bring the press head 2 down to the buck 1 and thereafter operates the handle 76, to operate the shifting lever 18 110 which controls the operation of the power lever 7 by the cam 17, and again arranges new work on the receiving end of the belt, while another operator removes the pressed work from the right hand portion of the belt. After the press has been closed a sufficient length of time, the operator again 115 operates the handle 76 to cause the lever 18 to again connect the cam to the actuating means, and causes another half revolution of 120

125

the cam, so that, the press opens up by the operation of the counter weight 20. He thereupon again presses the button 82 to cause the belt to travel another one-sixth of its length.

The garments may be steamed, that is, steam may be passed through the garments on the buck by any suitable means controlled by a handle 90 suitably connected by means 10 of suitable links to a valve 91. Preferably the handles 67, 76, 21 and push button 82 are grouped together so as to be conveniently operated.

What I claim is:—

- 15 1. In a pressing apparatus, the combination of a pressing machine, comprising co-acting pressing elements, one of which is movable toward and from the other, means for actuating the movable pressing element, 20 a conveyor belt movable over the face of the other element, motor means for actuating the belt, means controlled by the belt for controlling the amount of movement of the 25 belt by the motor means and operator operated means for controlling the actuation of the belt by the motor means.
2. In a pressing apparatus, the combination of a pressing machine, comprising co-acting pressing elements, one of which is movable toward and from the other, means for actuating the movable pressing element, a conveyor belt movable over the face of the other element, motor means for actuating the belt, means controlled by the belt for determining the amount of movement of the belt by the motor means, comprising shoulders on the belt at intervals, and a movable control member arranged in the

path of the shoulders and arranged to be actuated thereby. 40

3. In a pressing apparatus, the combination of a pressing machine, comprising co-acting pressing elements, one of which is movable toward and from the other, means for actuating the movable pressing element, 45 a conveyor belt movable over the face of the other element, motor means including an electric motor for actuating the belt, an automatic breaker switch for controlling the flow of current to the motor, a manually 50 operable switch for throwing the breaker switch to "on" position and a remote control controlled by the belt for throwing the breaker to "off" position.

4. In a pressing apparatus the combination of a pressing machine comprising co-acting pressing elements, one of which is movable toward and from the other power means for actuating the movable element, a work conveyor belt movable between the 60 pressing elements and extending beyond opposite sides of the pressing machine, a frame supporting the belt on opposite sides of the machine, power means for actuating the belt, operator operated means for controlling the 65 opening and closing of the press by its power means, operator operated means controlling the actuation of the belt, and means controlled by the belt for stopping the actuation of the belt by the power means. 70

In testimony whereof, I have hereunto signed my name, at Philadelphia, in the county of Philadelphia, in the State of Pennsylvania, this 10 day of April, 1924.

EDWARD J. SCHREMP.
